United States Patent Office

Des. 227,420
Patented June 26, 1973

227,420

BOOT

Tatsuo Fukuoka, 3,3-Ban, 2-chome,
Shin-Minami-Fukushima, Japan

Filed Nov. 4, 1971, Ser. No. 195,896

Claims priority, application Japan, Oct. 1, 1971

Term of patent 14 years

Int. Cl. D2—04

U.S. Cl. D2—275

FIG. 1

FIG. 2

FIG. 3

FIG. 4

FIG. 5

FIG. 6

FIG. 1 is a top plan view of a boot showing my new design;

FIG. 2 is a side elevational view thereof;

FIG. 3 is a bottom plan view;

FIG. 4 is a side elevation view of the side opposite that shown in FIG. 2;

FIG. 5 is a front elevational view; and

FIG. 6 is a rear elevational view.

I claim:

The ornamental design for a boot, substantially as shown.
